UNITED STATES PATENT OFFICE.

JOHN A. BRIDGE, OF LARIMER, PENNSYLVANIA, ASSIGNOR OF ONE-EIGHTH TO
LAWRENCE A. BRIDGE AND ONE-EIGHTH TO CHARLES C. PONITZ, BOTH OF
NORTH IRWIN, PENNSYLVANIA.

RAIL-JOINT CHAIR.

1,385,426.

Specification of Letters Patent.

Patented July 26, 1921.

Application filed April 30, 1921. Serial No. 465,787.

To all whom it may concern:

Be it known that I, JOHN A. BRIDGE, a citizen of the United States, residing at Larimer, in the county of Westmoreland and 5 State of Pennsylvania, have invented certain new and useful Improvements in Rail-Joint Chairs, of which the following is a specification.

This invention relates to improvements 10 in rail-joint chairs, and has for its particular object, to provide a device of this character which will hold the adjacent ends of the rails in alinement and automatically take up any lost motion that might be caused by jarring 15 or wearing of the parts. A further object is to provide means which will lock the holding parts in position, and also other means for preventing the pulling apart of the ends of the rails and at the same time allow suitable 20 clearance for expansion and contraction.

These objects are attained by the means illustrated in the accompanying drawing, in which:—

25 Figure 1 is a perspective view of the device applied to a rail-joint.

Fig. 2 is a horizontal sectional view taken substantially central of the rail.

30 Fig. 3 is a vertical section taken on the line 3—3 of Fig. 2, and showing the wedge in end elevation, and

Figs. 4 and 5 are detail views of the front washer and lock nut respectively.

35 Similar reference numerals in all of the figures of the drawing designate like parts.

Referring to the drawing it will be seen that the rail-chair is formed with a base 6 which extends beneath the rails, and side flanges 7 and 8 formed integral with the base 40 and adapted to lie alongside of the ends of the rails. Supporting flange 7 is formed to closely engage the flanges and webs of the adjacent rails on the inside of the track, and with its upper edge located close beneath and 45 in engagement with the head of the rails to serve as a support therefor, and wedge-flange 8 is formed to lie spaced from the webs of the rails and its inner face is constructed slightly inclined outwardly from its 50 front end to the rear end to form a wedge space 10 of varying width between it and the rails to receive a wedge-bar 9 for forcing the chair and the rails into tight relation.

The means provided for holding the wedge

in its tight relation, comprise a cover plate 55 11 adapted to be positioned on the front end of the chair, and provided with an aperture 12, through which is passed an extension rod 13 preferably formed integral with the wedge-member and projecting substantially 60 centrally from the front face thereof. The front end of rod 13 is screw-threaded to receive a lock-nut 14 which is adapted to engage against a washer 15 between which and the cover plate 11 is mounted a heavy coil-spring 16 that surrounds the rod 13. The inner edge of member 15 is shaped to conform to the web and upper face of the rail-flange, so that it will seat snugly and squarely thereon, and on its front face is 70 provided with a vertical groove 17 which is formed to the outside of the opening 18 through which the rod 13 passes, and said groove 17 is adapted to register with a vertical groove 19 formed on the rear side 75 of the nut, so that a pin 20 inserted in said grooves will lock the nut against accidental rotation.

Cover plate 11 has its inner edge 21 formed to conform with the shape of the 80 web and flange of the rail, and is provided on its outer edge with a lug 22 which is adapted to overlap the web-flange 8, as shown in Fig. 1 of the drawing, and said lug 22 is provided with a pin projection 23 85 adapted to enter an opening formed in the top side of the wedge-flange. The overlapping lug and its pin positively hold the cover plate in position and prevent its displacement under severe jolts and jars caused 90 by the trains traveling over the track.

The rear or larger end of the wedge 9 is provided with a recess or opening 24 adapted to receive a suitable tool used in removing the wedge from its wedging position. 95

Supporting-flange 7 is formed with a series of pins 25 which are adapted to enter openings 26 formed adjacent the ends of abutting rails. The openings 26 are slightly larger than the diameter of the pins 25, so 100 that the rails can expand and contract and at the same time be prevented from pulling apart.

Both flanges 7 and 8 are provided with projecting lugs 27 which are preferably 105 notched, as shown at 28, to receive the rail-spikes to retain the chair in position and prevent its creeping.

It will be apparent that with the parts assembled, as shown in Fig. 1 of the drawing, and with the spring 16 under compression, that any looseness at the joint would 5 at once be taken up by the spring which being under compression tends to force the nut 14 and washer 15, and consequently the wedge bar 9 to the left, or in the wedging direction.

10 From the above description taken in connection with the drawing, it will be observed that a rail-joint chair is provided which has stability, easy and simple to install, and one that will effectually hold the ends of the 15 rails in alinement and automatically tighten its grip upon the rails should any looseness occur.

Having thus described the invention, what is claimed is:—

20 1. A rail-joint chair, comprising a base adapted to lie beneath the rails and provided with an integral supporting flange adapted to engage one side of the rails and the underside of the rail-head, and a wedge- 25 flange extending upwardly and spaced from the other side of the rails and provided with an inner face which is inclined with respect to the sides of the rails to form a wedge-space between the rails and the wedge- 30 flange, a wedge-bar adapted to be forced into the wedge-space, and means connected to the small end of the wedge-bar for holding it in wedging position, including a spring mounted on an extension rod projecting from the small end of the wedge- 35 member and with locking means for forcing it under tension for automatically taking up loose motion.

2. A rail-joint chair, comprising a base 40 adapted to lie beneath the rails and provided with an integral supporting flange adapted

to engage one side of the rails and the underside of the rail-head, and a wedge-flange extending upwardly and spaced from the other side of the rails and provided with an 45 inner face which is inclined with respect to the sides of the rails to form a wedge-space between the rails and the wedge-flange, a wedge-bar adapted to be forced into the wedge-space, and means connected to the 50 small end of the wedge-bar for holding it in wedging position, including a spring with locking means for forcing it under tension for automatically taking up loose motion, 55 said locking means embodying a non-rotatable washer provided with a groove in one face, and a nut adjustably mounted on the end of the wedge-bar and also provided with a groove to register with the washer-groove, and a locking pin adapted to engage in the 60 registering grooves.

3. A rail-joint chair, comprising a base adapted to lie beneath the rail and provided with upwardly extending flanges adapted to lie on opposite sides of the rails, a wedge-bar adapted to be forced between one of said flanges and the sides of the rails and provided with an extension rod at its smaller end, a cover plate adapted to engage the end of the chair adjacent the small end of the wedge-bar and provided with an aperture to permit said extension rod to pass therethrough, a non-rotatable washer slidably engaged on the end of the extension rod, a spring mounted on the extension rod between the 70 cover plate and non-rotatable washer, a nut for forcing the washer against the spring to compress the same, and means for locking the washer and nut together.

In testimony whereof I affix my signature. 80

JOHN A. BRIDGE.
